ALARM BELL

Arthur W. Fruh, Chicago, Ill.

Application June 23, 1944, Serial No. 541,676

8 Claims. (Cl. 172—126)

1

This invention relates to alarm bells, and more particularly it relates to that type of alarm bells used in burglar or fire alarm systems. Among its objects is to simplify and otherwise improve upon the construction of bells of this character. Another object is to provide a solenoid for operating the striker head and having an armature guided by narrow non-metallic guide members whereby to minimize the friction between the armature and its guiding means and thereby obtain what may be termed a "floating" armature. Another object is to provide a resilient switch actuating blade with an adjustable connection with the armature whereby the length of the armature stroke may be varied. Another object is the provision of means for supporting domes of several different diameters in proper position relative to the striker head.

With these and other objects and advantages in view, this invention consists in the several novel features hereinafter fully set forth and claimed.

The invention is clearly illustrated in the drawings accompanying this specification, in which:

Fig. 1 is a front elevation of an alarm bell embodying one form of the invention, with the dome removed and illustrated in dotted lines;

Fig. 2 is a view partly in side elevation and partly in vertical section taken substantially along the line 2—2 of Fig. 1; and

Fig. 3 is a central vertical section of a fragment of a certain dome supporting post, an adapter and a dome of greater diameter, a fragment of the solenoid being illustrated in side elevation.

Referring to said drawings, the reference character 5 designates a base plate formed with obliquely extending arms 6, 7, having screw holes therein for receiving the bolts or screws that fasten the device upon its support. Mounted on the base plate is a solenoid 8, the windings 9 of which are contained in a metal cup-like shell 10 which is provided with wings 11 that are fastened to the base plate as by screws 12. The end wall or head 13 of the shell closes one end thereof and a disc 14 closes the opposite end which is peened over the edge of the disc. As usual, a fiber jacket 15 encloses the windings of the solenoid and a metal tube 16 is secured in the end wall 13 and disc 14 as by a press fit and provides the opening for receiving the armature 17.

Spaced from one end of the solenoid is a post 18 which is mounted upon the base plate and provides means to support the dome 19. The armature, to all intents and purposes, is a "floating" armature; it is guided to move in a right line

direction by two non-metallic guide members 20, 21, preferably composed of "Bakelite." The guide member 20 is in the form of a bushing held in the tube 16 by press fit and the guide member 21 may be in the form of a block secured to the post 18 as by screws 22.

Secured to one end of the armature is a striker head 23 which strikes the dome in sounding an alarm. The striker head may be formed with a screw threaded neck 24, threadedly secured in a threaded bore which extends in from the adjacent end of the armature. The striker head extends out through the hole in the guide member 20 and normally is spaced a short distance away from the skirt portion of the dome. Threadedly secured in a threaded bore in the opposite end of the armature is a stem or rod 25 which extends through a hole 18a in the post and is guided in an aperture in the guide member 21. A lock nut 26 is threaded upon the stem 25 and bears against a washer 27 interposed between the adjacent end of the armature and the lock nut. A light, coiled compression spring 28 is interposed between the washer 27 and the disc 14 of the solenoid and urges the armature in a direction opposite to that in which it is moved when the solenoid is energized. Desirably a resilient buffer block 29 encircles the stem 25 and absorbs any shock occasioned when the armature is thrust toward the guide member 21. Mounted on the base plate as by a screw 30 is an angle bracket 31, upon which is supported a switch 32, preferably in the form of a microswitch, the mechanism of which includes the usual actuating pin 36 which is operated by a resilient blade 33 fastened at one end upon one arm 34 of the bracket 31 as by screws 35. The blade extends along one face of the microswitch and when in its normal position it depresses the pin 36, thereby opening the circuit through the switch. The other end of the blade is held in the forked arm 37 of an angle bracket 38 which is fastened to the base plate by means such as a screw 39 which extends through a slot 40 in the angle bracket, thus permitting of adjustment of the angle bracket toward and away from the other support of the blade. A block 41 of rubber or other resilient composition is fastened upon the end of the blade and bears against the bracket.

The stem 25 extends through an aperture in the blade and is provided with a shoulder such as a nut 42 threaded upon the threaded end of the stem and adapted to bear against the blade and flex it in a direction away from the switch when

the solenoid is energized. A set nut 43 may be threaded upon the stem and screwed up against the nut 42 whereby to lock the nut in fixed position upon the stem.

The domes for alarm bells of the present character are usually made in a number of standard sizes, and means are provided for supporting domes of three standard sizes in proper relation to the striker head. In the drawings I have shown an eight inch dome 19, a ten inch dome 19a and a twelve inch dome 19b, together with means to support and properly locate each dome in relation to the striker head.

On the end of the post 18 is removably secured an arm 44 to the free end of which is secured a washer-like spacer 45 which positions the dome relative to the striking head. A bolt 46 threadedly secured in the arm 44 fastens the dome on its support. A pin 47 secured in the spacer extends through a hole in the dome and positively prevents rotation thereof and, if desired, a washer may be interposed between the head of the bolt and the dome. In the end of the post 18 is secured a pin 48 which extends through either of two diametrically opposite holes 49 in the arm 44. A bolt 50 threadedly secured in the post fastens the arm in place thereon and the pin 48 definitely locates the arm in either of its two dome supporting positions. In Fig. 2 the arm 44 is shown in full lines as occupying the position for supporting an eight inch dome 19. For supporting a twelve inch dome 19b the bolt 50 is unscrewed, the arm 44 is disengaged from the pin 48 and turned around 180 degrees, bringing it into the position illustrated in dotted lines in Fig. 2 and the bolt 50 is then screwed back in place. A twelve inch dome may now be bolted to the arm 44 and its spacer 45.

For supporting a ten inch dome 19a, a separate adapter 51 is provided, as seen in Fig. 3, which is interposed between the post and dome 19a and the latter is bolted to the post by a bolt 52. Rotation of the dome is positively prevented by a pin 53 which extends through registering holes in the post, adapter and dome. Desirably a washer 54 is interposed between the head of the bolt 52 and the dome.

Electrical conductors 55, 56 lead through the circuit closers of the alarm system in which the alarm bell is used, one conductor running to a binding post 57 of the microswitch and the other conductor running to one terminal of the solenoid winding, the other terminal of the winding being connected by an electrical conductor 58 with another binding post 59 of the microswitch.

In the operation of the alarm bell above described, when the electric circuit is closed through the microswitch, the solenoid is energized and the armature is propelled toward the dome with the striker head striking the same. In its movement toward the dome the nut 42 on the stem 25 flexes the blade 33 in a direction away from the pin 36, thereby permitting the pin to be urged outward from the switch case and opening the circuit through the microswitch, whereupon the spring 28 retracts the armature, and as a result the stem 25 and nut 42 are moved back releasing the flexed blade which immediately straightens out, depresses the pin 36 and again closes the circuit through the microswitch thereby repeating the same operation and sounding the alarm until the circuit is opened at some place in the system.

Having thus described my invention, it is ob-

vious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

- 10 1. In an alarm bell, the combination of a base plate, a solenoid mounted on said base plate and having an armature guided therein for movement axially thereof, a switch in series with said solenoid mounted on said base plate, said switch having an actuating pin, a resilient switch actuating blade mounted at both of its ends on said base plate and arranged to engage said actuating pin, and a stem secured to said armature and having a shoulder thereon for engaging said blade.
- 15 2. In an alarm bell, the combination of a base plate, a solenoid mounted thereon and having a shell for enclosing its windings, a dome supporting post mounted on said base plate, "Bakelite" guide means having aligned apertures therein, one guide means being secured in the shell of the solenoid and one secured on said post, and an armature guided for movement axially of said solenoid by said guide means.
- 20 3. In an alarm bell, the combination of a base plate, a solenoid mounted thereon and having a shell for enclosing the windings thereof, a switch in series with said solenoid mounted on said base plate, a dome supporting post mounted on said base plate, a "Bakelite" guide bushing secured in said shell and a "Bakelite" guide block secured on said post and having an aperture therein coaxially aligned with said bushing, and an armature having a striker head secured on one end and a switch blade actuating stem on the other end with blade engaging means adjustably mounted thereon, said striker head and stem being guided in said bushing and block respectively.
- 25 4. In an alarm bell, the combination of a base plate, a solenoid mounted thereon and having a shell for enclosing the windings thereof, a post mounted on said base plate, a "Bakelite" guide bushing secured in said shell and a "Bakelite" guide block secured on said post and having an aperture therein coaxially aligned with said bushing, and an armature having a striker head secured on one end and a switch blade actuating stem on the other end, said striker head and stem being guided in said bushing and block respectively.
- 30 5. In an alarm bell, the combination of a base plate, a dome supporting post mounted thereon, a solenoid mounted on said base plate and having an armature guided therein for movement axially thereof, and a blade actuating stem on its other end with blade engaging means adjustably mounted thereon, a bracket mounted on said base plate, a microswitch carried by said bracket, a resilient blade, one end of which is carried by said bracket and engaging a switch actuating pin, a second bracket mounted on the base plate for holding the other end of the blade, said switch being electrically connected in series with the windings of the solenoid.
- 35 6. In an alarm bell, the combination of a base plate, a dome supporting post mounted thereon, a solenoid mounted on said base plate and having an armature guided therein for movement axially thereof, and a blade actuating stem on its other

end, a bracket mounted on said base plate, a switch in series with said solenoid carried by said bracket, a resilient blade, one end of which is carried by said bracket and engaging a switch actuating pin, a second adjustably mounted bracket mounted on the base plate for holding the other end of the blade, and a spring for urging the armature toward the blade.

7. In an alarm bell, the combination of a base plate, a solenoid mounted on said base plate and having an armature guided therein for movement axially thereof, a microswitch in series with said solenoid, said switch having an actuating pin, a bracket for supporting said switch on the base plate, a resilient switch actuating blade arranged to actuate said pin, a bracket for supporting one end of said blade in close proximity to said switch, a bracket for supporting the other end of said blade, and a threaded stem secured to said armature and having a nut thereon arranged to flex said blade and therewith open the contacts of the microswitch.

8. In an alarm bell, the combination of a base plate, a solenoid mounted on said base plate and having an armature guided therein for the movement axially thereof, a bracket secured to said base plate, a microswitch in series with said solenoid, mounted upon said bracket, said switch having an actuating pin, a resilient switch actuating blade arranged to actuate said pin, said blade being mounted at one end upon said bracket in close proximity to the switch, a second bracket secured to said base plate for supporting

the other end of said blade, a threaded stem secured to said armature and having a nut thereon arranged to flex said blade and therewith open the contacts of the microswitch, and a coiled compression spring surrounding said armature and engaging a shoulder thereon.
